TOW BOAT

Jerry L. Holtgrewe, St. Louis County, Mo.
(725 Benvenue Drive, St. Louis 37, Mo.)

Filed May 16, 1963, Ser. No. 74,914

Term of patent 3½ years

(Cl. D71—1)

FIG. 1.

FIG. 2.

FIG. 3.

FIG.4.

FIG.5.

FIG. 1 is a top plan view of a tow boat, showing my new design;

FIG. 2 is a right side elevation thereof;

FIG. 3 is a front elevation thereof;

FIG. 4 is a left side elevation thereof; and

FIG. 5 is a rear elevation thereof.

I claim:

The ornamental design for a tow boat, substantially as shown.
